2 SHEETS—SHEET 2.

UNITED STATES PATENT OFFICE.

NATHANIEL METZ, OF LANSDALE, PENNSYLVANIA, ASSIGNOR OF ONE-HALF TO
WILLIAM D. HEEBNER, OF LANSDALE, PENNSYLVANIA.

INTERNAL-COMBUSTION ENGINE.

957,788.

Specification of Letters Patent. Patented May 10, 1910.

Application filed September 13, 1906. Serial No. 334,421.

To all whom it may concern:

Be it known that I, NATHANIEL METZ, a citizen of the United States, residing at Lansdale, county of Montgomery, State of Pennsylvania, have invented a new and useful Internal-Combustion Engine, of which the following is a specification.

My invention consists of a novel construction of an internal combustion engine, where-
10 in I employ a cylinder having a piston chamber of uniform bore, said cylinder having therein a plurality of pistons connected to a common crank shaft and provision being made for the charge of explosive mixture to
15 be drawn into the cylinder by suction created by the movement in the proper direction of the two pistons, said mixture being compressed by the inward movement of the pistons and ignited by suitable mechanism and
20 the exhaust being expelled through the suitable exhaust passages at the proper intervals.

By my invention, I produce a compact and comparatively light explosive engine or
25 motor which is especially designed for propelling all manner of vehicles, such as wagons, coaches, carriages, boats, railway passenger and other cars and machinery or appliances in general which require the application of propulsive power and it will be
30 evident to those skilled in the art that I may employ any suitable explosive mixture in order to actuate the two pistons.

To the above ends my invention consists of
35 a novel construction of intake end of the cylinder, its rear piston, and admission valve, whereby the cylinder and piston are properly cooled, said cylinder being provided with two pistons and having side passages
40 and a crank casing, the side connecting rods working through the side passages, whereby space is economized and the engine is rendered self-contained and not liable to injury from external sources.

45 For the purpose of illustrating my invention, I have shown one form of machine, as this embodiment best illustrates the principle of the invention, although it is obvious that the principal instrumentalities of which
50 my invention consist can be variously arranged and organized and in the accompanying drawings I have shown one embodiment thereof which I have found in practice to give satisfactory results, although it

is to be understood that my invention is not limited to this specific arrangement and organization of these instrumentalities.

Figure 1 represents a longitudinal sectional view of an internal combustion engine embodying my invention. Fig. 2 represents
60 a section on line $x-x$, Fig. 1. Fig. 3 represents a section on line $y-y$, Fig. 1, showing the construction of blower or cooling device employed. Fig. 4 represents a longitudinal section on line $z-z$, Fig. 1. Fig. 5 represents a section on line $w-w'$, Fig. 1. Fig. 6 represents a plan view of the igniting device employed. Figs. 7 and 8 represent side elevations, viewed in different directions, of the igniting device seen in Fig. 6. Figs. 9,
70 10, 11 and 12 represent perspective views of the valve plate, washer, disk and bolt employed, in detached position.

Similar numerals of reference indicate corresponding parts in the figures.

75 Referring to the drawings:—1 designates my novel construction of internal combustion engine, the same comprising the cylinder 2 having therein the piston chamber, which it will be noted, is of uniform diameter, whereby the same can be cheaply and conveniently bored. The engine cylinder 2 is adapted to telescope or be contained in the outer cylinder 3 which terminates in the crank casing 4, wherein is contained the 80 crank 5, the same comprising the center cranks 6 and 7 connected by the center crank pin 8 and the end cranks 9 having the crank pins 10 as will be understood from Fig. 13.

85 11 designates the center connecting rod, one end of which is mounted on the center crank pin 8, with its opposite end pivotally connected to the lugs 12 of the front piston 13, the latter being hollow as will be understood from Fig. 1.

90 14 designates the outer connecting rods which engage the crank pins 10 and are located within the side ports 15, said connecting rods 14 having their rear ends connected to the rear piston 16, whose internal construction will be understood from Fig. 1. The piston 16 is provided with the transversely projecting pin or stud 17 whose ends travel in the slots or ports 18, the extent of which will be understood from the left hand 100 of Figs. 1 and 4, it being apparent that by the employment of the opposed cranks and the outer connecting rods 14 and the central

connecting rod 11, the engine is perfectly balanced in respect to all its reciprocating parts under all conditions.

It will be seen that by the above described arrangement of parts, it is possible for the intake and exhaust ports, to be hereafter referred to, to extend around the whole circumference of the cylinder walls, leaving only the necessary metal for the bridges to 10 guide the piston rings over the ports, thus insuring free exhaust and full intake of charge of gas into the cylinder at the proper intervals.

19 designates the intake port, the same being located preferably at the rear end of the cylinder and opening into the cap or closure 20, whereby the intake valve and its adjuncts are conveniently held in assembled position with respect to the end of the cylinder. The construction of the intake valve will be apparent from the left hand portion of Figs. 1 and 4 and Figs. 9 to 12 inclusive, said valve comprising the plate 21 having the ports 22 therein, against which plate is 25 seated the flap or washer 23 of leather or other suitable flexible material, said washer having the opening 24 therethrough.

25 designates a disk having the extension 27 partially closed by the plate 28 which has 30 the opening 29 therethrough.

30 designates a bolt or other fastening device which passes through the opening 31 of the plate 21 through the opening 24 of the disk 23 and thence through the opening 29, said bolt being adapted to co-act with a spring 32 so that the parts as assembled will appear substantially as seen at the left of Fig. 1, whereby at the proper intervals the parts 23 and 25 will be permitted to move to 40 and from the plate 21, the outer edge of the flap 23 being held stationary, as will be apparent to those skilled in this art.

It will be apparent that as the pistons move from the position seen in Figs. 1 and 45 4 toward each other, gas will be drawn through the intake 19, the intake valve and its adjuncts into the interior of the rear piston 16 to cool it, this piston being exposed to the greatest heat at the time of exhaust.

50 The gas, after filling the rear piston 16, passes through the side ports 18 and the longitudinal ports or passages 15 to the crank casing 4 and around the outside of the cylinder to the combustion chamber. By this 55 arrangement, the cranks and connecting rods in the crank chamber can be lubricated by the splash system without drawing too much oil into the cylinder.

60 The intake valve at the rear end of the cylinder is in practice constructed of sufficient size to freely admit the gas from the carburetor (not shown) and can be made of either leather or metal or other suitable materials, as will be apparent to those skilled 65 in the art.

The construction I have thus far described, admits either of the apparatus being air or water cooled and by using the usual valves, can be made four-cycle as will be apparent to those skilled in the art.

70 33 designates a lug on one side of the connecting rods 14, the latter being adapted to actuate at the proper intervals, the pin 34 and thereby force the contact spring 35 toward the contact point 36, said pin 34 being carried in the disk 34* in the threaded plug 37 which disk has the handle 38 secured to it, whereby the disk and its adjuncts can be rotated according to requirements.

75 39 designates the intake ports which are in communication with the side ports 15, while 40 designates the exhaust ports which are opened at the proper intervals to permit of the escape of the products of combustion after the piston 16 has moved to the proper extent.

80 41 designates a casing containing the fan 42 which is mounted on the shaft 44 having suitable bearings in said casing 41, said shaft carrying thereon, blades 45 whereby the force 90 of the exhaust causes the fan to revolve very rapidly which also acts as a muffler for the engine, the final exhaust taking place through the outlet 43, seen in Fig. 1, it being apparent that the fans or blades 42 cool 95 the outside of the motor case and may be of such contour as to direct the currents of air to the desired parts of the piston cylinder as required. One of the ports 40 may if desired communicate directly with the atmosphere instead of communicating with the blowing mechanism.

100 The operation will be apparent to those skilled in the art, since it will be clear that as the pistons 13 and 16 reciprocate at the proper periods the charges of gas will be forced into the space between said pistons and compressed and ignited at the proper intervals by the contact of the lug 33 with the contact device 34 as will be understood 110 from the enlarged views seen in Figs. 6 to 8 inclusive. The ignition having taken place, the pistons 13 and 16 will move away from each other and as the piston 16 uncovers the exhaust port 40, the exhaust to the atmosphere will take place simultaneously therewith, will cause the fan 42 to rotate and with it the blades 45, thus directing the current of air to the portions of the engine 115 cylinder.

120 It will be apparent that I have omitted some of the ports and passages from certain figures of the drawings for the sake of clearness of illustration, since the operation of engines of this class will be clearly apparent 125 to those skilled in this art.

In practice I construct the rear piston 16 with ports 46, whose function is to permit the escape of gas through the ports 18 and side passages 15 when the piston 16 moves 130

rearwardly or toward the intake valve and its adjuncts; otherwise too much of a cushioning action would take place, which would be detrimental to the efficient operation of the engine. The contact device seen in Figs. 5 to 8 and at the upper portion of Fig. 4 is simple and effective in operation and admits of advancing the spark and by simply moving the lever or handle 38 above or below 10 the center, the engine will run either way forward or backward according to requirements.

The raised contact, cam or lug 33 on the connecting rod allows the rod to pass the 15 contact point at the other end of the stroke without making contact.

I desire to call especial attention to the location and co-action of the intake valve and the rear piston 16, since it will be apparent that said piston, being exposed to 20 great heat at the time of exhausting, will tend to become very hot, but by my arrangement of parts the cold gas will be drawn into the hollow piston 16 initially as soon as 25 said piston moves away from the intake valve, whereby said piston will always be cooled to the desired extent.

I have deemed it unnecessary to show or 30 describe in detail the construction of the carbureter or the electrical details of the mechanism for timing the action of the electric spark, which may consist of a battery, spark coil or the like, as the same *per se* forms no part of my present invention.

35 It will be apparent that changes may be made by those skilled in the art which will come within the scope of my invention and I do not therefore desire to be limited in every instance to the exact construction here- 40 in shown and described.

Having thus described my invention, what I claim as new and desire to secure by Letters Patent, is:

1. In an internal combustion engine, a cylinder, front and rear pistons therein, an intake valve at the rear of said cylinder, said rear piston being open at its rear end and adapted to receive and be cooled by the gas entering through said valve, ports at the 45 rear end of said cylinder, a crank case, side passages communicating with said ports and said crank case, inlet and exhaust ports in the cylinder, said inlet ports communicating with said passages, a crank shaft in the 50 crank case, side connecting rods in said passages and secured to said crank shaft and to the rear piston, and a central connecting rod secured to said crank shaft and said front piston.

60 2. In an internal combustion engine, a cylinder, an intake valve at the rear end thereof, front and rear pistons in said cylinder, said rear piston being open at its rear end and adapted to receive and be cooled by 65 the gas entering through said valve, ports

in said cylinder at its rear end, side passages communicating with said cylinder ports, a crank case communicating with said side passages, center cranks and end cranks in said crank case, side connecting rods secured 70 to said rear piston and to said end cranks, a central connecting rod secured to said center cranks and said front piston, ports in said rear piston communicating with the ports at the rear of the cylinder on the rearward movement of the rear piston, means for admitting the charge from the side passages to the space between the pistons, and means for exhausting the burned gases. 75

3. In an internal combustion engine, a cylinder, an intake valve at the rear end thereof, front and rear pistons in said cylinder, said rear piston being open at the rear end and adapted to be cooled by the charge entering through the intake valve, ports at 80 the rear end of the cylinder, a crank casing, center cranks and end cranks therein, side passages communicating with said ports and the casing, connecting rods located in said 85 passages and secured to the end cranks, means passing through said ports for securing the connecting rods to the rear piston, a central connecting rod secured to the center cranks and to the front piston, inlet ports 90 from said side passages to the cylinder and controlled by said front piston, exhaust ports controlled by said rear piston and ports in said rear piston intermediate the ends thereof and adapted to register with the ports at 95 the rear end of the cylinder on the rearward movement of the rear piston. 100

4. In an internal combustion engine, a cylinder, front and rear pistons in said cylinder, an intake valve at the rear of said cylinder, said rear piston being open at its rear end and adapted to receive and be cooled by the gas entering said valve, ports in the side wall of the rear piston, a pin extending transversely of said rear piston, ports controlled by said rear piston located at the 110 side of said cylinder and adapted to receive and guide the ends of said pin and co-operating with said piston ports to permit a charge to pass through the side passages on the rear stroke of the rear piston, there being side passages communicating with and leading from said cylinder ports, a crank case with which said side passages communicate, a crank shaft therein, side connecting rods leading from said crank shaft to said 115 pin, a central connecting rod leading from said crank shaft to said front piston, means for admitting the charge from the side passages to the space between the pistons, and means for exhausting the burned gases. 120
